CLAIM

The ornamental design for a seating furniture as shown and described.

DESCRIPTION

FIG. 1 is a front perspective view of a first embodiment of a seating furniture showing my design;

FIG. 2 is a rear perspective view thereof;

FIG. 3 is a left side perspective view thereof;

FIG. 4 is a right side perspective view thereof;

FIG. 5 is a top view thereof;

FIG. 6 is a bottom view thereof;

FIG. 7 is a front perspective view of a second embodiment of a seating furniture showing my design;

FIG. 8 is a rear perspective view thereof;

FIG. 9 is a left side perspective view thereof;

FIG. 10 is a right side perspective view thereof;

FIG. 11 is a top view thereof; and,

FIG. 12 is a bottom view thereof.
